UNITED STATES PATENT OFFICE.

ANTON V. KERPELY, OF VIENNA, AUSTRIA-HUNGARY.

GAS-GENERATOR.

No. 826,036.

Specification of Letters Patent.

Patented July 17, 1096.

Application filed January 21, 1905. Serial No. 242,164.

To all whom it may concern:

Be it known that I, ANTON VON KERPELY, a subject of the Emperor of Austria-Hungary, residing at Vienna, Austria-Hungary, have 5 invented certain new and useful Improvements in Gas-Generators, of which the following is a specification.

This invention has for its object the construction of a gas-generator in which caking 10 together of the coal is prevented and an intense gasification secured. For these purposes the coal in the generator is kept in continual motion, the rotating bottom of the generator being provided with a grate of polygonal or elliptical outline arranged vertical to 15 the axis of rotation.

In the accompanying illustrative drawings, Figure 1 shows in longitudinal vertical section a construction of generator according to 20 this invention. Fig. 2 is a horizontal section thereof.

The fuel is fed through the coal-charging apparatus *c* at the top into the double-walled water-cooled jacket *b* of the generator-body, 25 which is rigidly mounted upon supporting-brackets *a*. The lower end of the jacket *b* dips into a rotary trough *g*, mounted on balls *f* and preferably constructed of cast-iron. The outer periphery of the trough *g* is provided with a ring of teeth *h*, into which gears 30 a work *k*, driven by a motor *i*, so that the trough *g* can be caused to rotate in the direction of the arrow, Fig. 2. Upon the trough *g* is situated a tower-like grate *m*, which projects into the generator and which, according 35 to this invention, is formed of rings *s*, provided with lateral air-openings *r*. The rings have a polygonal outline in plan, as shown in Fig. 2, or may be of elliptical shape, the object being to have portions of the periphery of the pyramid at a greater radial distance 40 from the center than others, so that these projecting portions or corners *t* will break up the material and prevent it from agglomerating or caking.

Air is supplied to the generator through the air-supply pipe *n* to the interior of the

central pyramid and passes out of the same through the openings *r*.

The fuel supplied to the generator through 50 the coal-charging apparatus *c* is during the rotary motion of the trough *g* and its grate *m* kept in continual movement by the corners of the polygonal rings or by the extending ends of the elliptical rings corresponding to 55 the difference of axes, so that caking together of the coal is prevented. Moreover, during this rotary movement of the grate, owing to the angular or rounded-off extensions *t* of the grate, a very much larger surface area than 60 the actual area of the grate is acted upon and the supply of air through the grate takes place over this larger surface. At the same time the air to support combustion is uniformly distributed among the fuel and the 65 gasification materially enhanced.

In a generator constructed according to this invention a considerably larger quantity of coal can be gasified than is possible with known generators of similar size.

I claim—

1. In a gas-producer, the combination with a stationary producer-body, of a grate comprising a plurality of graduated superposed perforated polygonal rings, and means 75 to rotate said rings.

2. In a gas-producer, the combination with a stationary producer-body, of a grate mounted therein comprising a plurality of laterally-perforated vertically-graduated polygonal rings, and means to rotate said rings.

3. In a gas-producer, the combination with a stationary producer-body, of a grate comprising a plurality of graduated lozenge-shaped laterally-perforated rings, the upper 85 faces of said rings lying in parallel horizontal planes, and means to rotate the rings.

In testimony whereof I have hereunto set my hand in presence of two subscribing witnesses.

ANTON V. KERPELY.

Witnesses:

ALVESTO S. HOGUE,
AUGUST FUGGER.
